(57) **CLAIM**

The ornamental design for a glide sheet for display rack, as shown and described.

DESCRIPTION

FIG. 1 is a top, left and rear perspective view of a glide sheet for display rack showing the new design;

FIG. 2 is an enlarged detail view of area 2 circumscribed within FIG. 1;

FIG. 3 is an enlarged detail view of area 3 circumscribed within FIG. 1;

FIG. 4 is a front view of the glide sheet for display rack of FIG. 1;

FIG. 5 is an enlarged detail view of area 5 circumscribed within FIG. 4;

FIG. 6 is a rear view of the glide sheet for display rack of FIG. 1;

FIG. 7 is a right side view of the glide sheet for display rack of FIG. 1;

FIG. 8 is an enlarged detail view of area 8 circumscribed within FIG. 7;

FIG. 9 is a left side view of the glide sheet for display rack of FIG. 1;

FIG. 10 is a top view of the glide sheet for display rack of FIG. 1; and,

FIG. 11 is a bottom view of the glide sheet for display rack of FIG. 1.

The dot dash broken lines depict the boundaries of the areas of the enlarged details and form no part of the claimed design.

1 Claim, 7 Drawing Sheets
